DANIEL SIMMONS, JR., OF NEW YORK, N. Y.

Letters Patent No. 100,198, dated February 22, 1870.

IMPROVEMENT IN PAPER-BOX MACHINES.

The Schedule referred to in these Letters Patent and making part of the same.

To all whom it may concern:

Be it known that I, DANIEL SIMMONS, Jr., of the city and State of New York, have invented and made a new and useful Improvement in Formers for Paper-Box Machines; and I do hereby declare the following to be a correct description of the same.

In the manufacture of paper boxes, a former has been employed that is divided into sections to be expanded within the ring of paper forming the cylindrical portion of the box, to shape the same and support it while the bottom is introduced and secured.

My invention relates to the former itself, wherein a contractile metallic ring is combined with a clamping-spring in such a manner as to receive and hold the end of the strip of paper while being rolled up to form the cylindrical part of the box and receive the bottom or disk of paper, and be attached thereto by the external covering paper. After this the ring is allowed to contract and free itself from the box as the former is withdrawn.

The mechanism for operating the former, pressing up the disk of paper forming the top or bottom of the box, pressing on the covering paper, and otherwise finishing the box, being well known, need not herein be described, especially in view of the fact that a machine of this kind forms the subject of a separate application for a patent heretofore filed by Daniel Simmons.

In the drawing—

Figure 1 is a face view of the former with the ring contracted;

Figure 2 is a similar view with the ring expanded;

Figure 3 is a section longitudinally of the axis of the former;

Figure 4 is a view sidewise of the expanding-ring; and

Figure 5 shows a portion of the arbor of the former.

The arbor *a* is formed of a pipe, so as to be revolved upon any suitable gudgeon. The recess *b* in said arbor allows a clutch or lever to be applied at this point for moving the arbor *a* and former endwise upon its supporting gudgeon, to bring said former up against the disk of paper or draw said former back for taking off the box.

The block *c* surrounds the arbor *a*, and can slide thereon. The arbor *a* is made as a square bar or

prism between the collar *2* and the pyramidal frustum *3*, and the block *c* slides upon this square bar, and is limited in its movement by said collar *2* and frustum *3*.

The block *c* is cylindrical, and of a size smaller than the box to be made, and said block *c* is either solid or made of pieces secured permanently together, to facilitate manufacture or repair.

Around the block *c* is the contractile metallic ring *f*, that is made with a central tongue, *4*, between two side tongues, *5*, (see fig. 4,) so that this ring *f* can be expanded to the size of the interior of the box by the pyramidal frustum *3* acting upon the inner ends of the studs *h*, that project inwardly from the ring *f* through mortises in the block *c*, that allow of the motion of the studs *h* as the ring is expanded by the endwise movement of the block *c* and parts upon the arbor *a*, or the ring allowed to contract by the reverse movement.

In order to hold the end of the strip of material that is wound around the ring *f*, when expanded, I make use of the spring-clamp *k*, having teeth, *7*, at one end, being attached at the other end, and having the latch *i* extending from the inner side of the clamp *k* to the angle of the pyramidal frustum *3*.

This angle of the frustum is made with an incline, *8*, and a catch, *9*, and as the block *c* is slipped back, the incline *8* lifts the latch *i*, and the spring-clamp *k* at the same time that the ring *f* is expanded by the frustum *3* acting upon the studs *h*. When the end of the strip of material has been entered under the end of the clamp *k*, that clamp is pressed down, and the end of the latch *i* takes the catch *9*, holding the material firmly, and when the box is formed and the arbor *a* is drawn back, the catch *9* draws away from the latch *i*, at the same time that the studs *h* are liberated, the ring contracts, and the box is free to be removed.

I claim as my invention—

The block *c*, arbor *a*, and pyramidal frustum *3*, in combination with the contractile ring *f*, studs *h*, spring-clamp *k*, and latch *i*, substantially as set forth.

Dated December 22, A. D. 1869.

DANIEL SIMMONS, JR.
